JOSEPH GOUGH, OF NEWARK, NEW JERSEY, ASSIGNOR TO GOUGH STEMMING MACHINE CORPORATION, A CORPORATION OF NEW JERSEY.

LEAF STEMMER.

Application filed January 15, 1924. Serial No. 686,262.

Machines for extracting the long center veins from the blades of tobacco leaves and the like, customarily called stemmers, usually comprise a mechanism which pulls the stem 5 or long vein through a device through which the leaf blade cannot follow, and by means of which accordingly the blade is stripped from the stem. The stripping device usually resembles a brush or comb, or card clothing, 10 but these two essential parts of stemmers may assume various forms and cooperate in various ways. Such machines are not entirely effective however inasmuch as they frequently break the stems prematurely, thus leaving 15 too much of the long veins in the blade. I have found that much of this grievance may be eliminated by occasionally relieving the pull on the stem during the course of the operation and preferably fully releasing the hold 20 of the pulling mechanism on the stem, so that the strain is occasionally relieved on both the stem and the blade during the stemming operation; the operation is performed therefore in a series of steps, or by means of a series 25 of two or more short pulls rather than by a single continuous long pull designed to extract the entire main vein from the blade in a single movement. This method of operating materially reduces the number of failures, and in addition to this method of operation I have developed and disclose herein an improvement on a known form of machine whereby it is made to operate in accordance 30 with my method. It will be obvious, however, that other forms of machines may also be adapted to operate in accordance with this method.

The accompanying drawings illustrate my invention applied to a known type of machine 40 as aforesaid. Fig. 1 shows the same in elevation and somewhat diagrammatically; Fig. 2 is a plan view thereof; Fig. 3 is a detail of the stem extracting operation; and Fig. 4 is a larger elevation of one of the stem gripping rolls of the preceding figures.

As is well known, at the entrance end A of the machine illustrated the leaves are laid on flexible conveyor belts 1, 2 and 3 with the ends of their stems substantially against the 50 vertical guide board 4 which thus assures that the leaves will be passed through the machine and subjected to its operations in a uniform manner. These belts and the others hereinafter mentioned, move continu-

ously and at a uniform speed and are supported and driven by rollers which are carried in the machine framing 5, but which need not be and for the most part are not illustrated in the present drawings. The belt 3 terminates shortly in advance of the 55 "butting" brushes 8. At this point, the leaves pass underneath a short run of belt 9 of some weight, which is usually in the form of an endless chain of flat metal links travelling at the same speed as the belts 1, 2 and 3; this 60 belt 9 presses the leaves against the belt 2 to prevent their endwise displacement during the operation of "butting" or cleaning the stems by the pair of brushes 8. These brushes are substantially cylindrical in shape (reduced in size at their ends, to admit the leaves between them) and are set nearly at 65 right angles to the approaching leaves; they are rotated by their supporting shafts 10 which in turn are driven by suitable mechanism (usually from the same power source as drives the belts) the details of which form no part of this invention and are not shown. As the butts of the leaves pass between these 70 brushes, the latter sweep the stems clear of 75 blade for some short distance back from their ends so that clean smooth butts are presented to the stem grippers and the blade stripping mechanism. At the stemming or blade stripping region, the machine is provided with a 80 wide belt 13 which lies underneath the belts 1 and 2 and also projects for some distance underneath the cleaned butts or stems where it is covered with card-clothing 14 or otherwise provided with stiff teeth of wire or suitable material (Fig. 3). Cooperating with 85 these upwardly projecting teeth to complete the blade stripping mechanism of the machine, is a belt or chain 15 (herein shown as slightly longer than the belt 13) which preferably comprises two parallel rows of hinged 90 links having brush faces of a suitable material (Fig. 3); the links of one chain are placed opposite the hinges of the other. The co-operating stripping belts 13 and 15 travel at 95 the same speed as the belts 1 and 2 and are so placed that the ends of the butts or stems of the leaves project beyond the teeth of the stripping belts 13 and 15 to a point within the grasp of the stem gripping mechanism. Customarily (in this form of stemmer) this 100 mechanism consists of a pair of generally conical rolls 18 and 19, having their axes

placed at nearly right angles to the leaf stems and spaced far enough apart to receive but firmly grip the leaf stems (Figs. 1, 2 and 3). In the present instance the lower roll 19 has 5 been modified in accordance with the invention as later explained. These two rolls are also power driven and are driven at such a speed with respect to the speed at which the leaves are conveyed laterally by the various 10 belts that the rolls pull the stems or long veins from the blades before the leaves pass beyond the reach of the stripping belts 13 and 15. As each stem is pulled, its blade is bunched up against the teeth of the stripping 15 belts (Figs. 2 and 3) and is withdrawn from the belt 1 but remains on or above the belt 2. The belt 2 terminates a short distance beyond the ends of the stripping belts 13 and 15 and at this point the stemmed blades fall to the 20 floor; the upper belt 22 and stationary wires 23 and 24 assure the leaf blades being extracted from the stripping belt teeth should they tend to remain tangled therein. The stems are discharged from the rolls into the 25 trough 25. Those leaves which fail to come within the reach of the stem gripping rolls 18 and 19, or in which the stems are broken before a suitable length is extracted from the blade, continue on the belt 1 which extends 30 beyond the end of the belt 2 as shown at the left in Fig. 2, so that the failures are dropped into a pile separate from the pile of suitably stemmed blades dropped from the end of 2. A belt 26 above the rear end of belt 1 helps 35 to retain the failures on belt 1 and prevents some inadvertent dropping of failures as the latter leave the belt 2. Various other details of the machine are illustrated in the figures more or less diagrammatically, but form no 40 part of the present invention and need not be described. Numerous leaves 27 are shown in progress through the machine.

Heretofore the two stem gripping rollers have been like the upper roller 18 illustrated in Figs. 1 and 2. That is to say, each has assumed the general form of a truncated cone curved or rounded at its forward end so that the leaf stems are guided into the narrow space between the rolls, although sometimes 45 grooved more or less longitudinally. Such rolls exert a continuous pull on each leaf stem and endeavor to extract the long vein of the leaf by a single long pull and in a single movement. In accordance with my invention, I 50 preferably provide a deep circumferential groove, as at 28, in at least one of these conical rolls; in the present instance the lower roll 19 is grooved in this manner, and in effect this 55 groove divides the roll into two longitudinally separated conical rolls, and separate rolls 60 may be used in the stead of the two stem gripping portions 29 and 30 of the single roll 19 illustrated. It is usually unnecessary to 65 provide such a groove or circumferential space in both the members 18 and 19 of the

roll group. The roll groove 28, or circumferential space, I preferably make so deep that the grip of the rolls on the stem is substantially entirely released at this point. In operation, the forward portion 29 of the roll 70 19 cooperates with the upper roll 18 to grip the stem initially and partly extract it. As the stem reaches the grooves 28 however the strains on the stem and blade are relieved momentarily and the resiliency of the partly 75 bunched blade is allowed to retract the stem somewhat and the blade is allowed to re-arrange itself somewhat in its relations to the blade strippers 13 and 15. Subsequently, the rear conical portion 30 of the roll 19 (cooperating with the roll 18) resumes the grip on the stem and completes the stem extraction. The pull on each stem is relieved therefore during the course of the stemming operation, and in this instance the stem is fully released in the 80 course of the operation, and the complete operation is performed in a series of steps and by means of a series of short pulls rather than by means of a single long continuous pull. This I find materially reduced the number of 85 failures as aforesaid, that is to say, reduces the number of leaves in which the principal long vein is broken before a sufficient part of it is extracted from the blade, and it is obvious that the same method may be adopted 90 in other forms of stemmer mechanisms. The forward end of the rear roll or roll portion 30 may be suitably sloped as shown like the fore ends of the roll group 18 and 19, to guide 95 the stem into position between 30 and 18. 100

It will be understood that my invention is not limited to the details herein shown and described but is set forth in the following claims.

Claims—

1. The method of extracting the stems from leaves which consist in exerting a series of pulls on the leaf stem while retaining the blade, each of which pulls partially extracts the stem, and relieving the strain intermediate pulls. 110
2. The method of extracting the stems from leaves which consists in exerting a series of pulls on the leaf stem, lengthwise thereof and thereby bunching the leaf blade against a device through which the blade cannot follow the stem, each pull partly extracting the stem, and relieving the strain on the stem intermediate pulls. 115
3. The method of extracting the stems from leaves which consists in exerting a series of pulls on the leaf stem, lengthwise thereof and thereby bunching the leaf blade against a device through which the blade cannot follow the stem, each pull partly extracting the stem and releasing the stem intermediate pulls. 120
4. The method of extracting the stem from a leaf which consists in drawing the stem lengthwise through a toothed structure 130

through which the blade cannot follow, and occasionally relieving the strain on the stem during the course of the operation.

5. In a leaf stemmer, the combination of a toothed stripping device moving with and transversely of the leaves, and mechanism to grasp the stems and pull the stems through said moving stripping device, said mechanism including successive rolling surfaces to 10 grasp and pull the stems, said successive rolling surfaces being spaced apart in a direction substantially parallel to the direction of movement of the toothed stripping device so that a succeeding rolling surface grasps 15 and pulls on a stem after a preceding rolling surface has grasped and pulled on the same stem and so that the pull on that stem is relieved during the stem-extracting operation.
20. 6. In a leaf stemmer, the combination of a toothed stripping mechanism moving with and transversely of the leaves and through which the stems of the leaves project, and a pair of co-operating conical rollers to grasp 25 the projecting stems and pull the same through said stripping mechanism, one of said rollers comprising a plurality of longitudinally-separated stem-pulling members between which the pull on the stems is relieved.
30. 7. In a leaf stemming mechanism, the combination of cooperating toothed blade-stripping belts moving with and transversely of

the leaves and between which the stems of the leaves are received, and a pair of cooperating 35 conical roller means to grasp the leaf stems and pull the same lengthwise through said moving belts, one of said conical roller means comprising a pair of longitudinally-separated 40 stem-pulling members between which the stems are substantially released and the forward ends of both of said pulling members being shaped to guide the stems into stem pulling position.

8. In a leaf stemming machine, the combination of blade-stripping means moving with and transversely of the leaves and from which the leaf stems can be drawn but through which the leaf blades cannot pass, and mechanism for grasping the stems and 50 intermittently pulling each stem, by separate steps, from said blade-stripping means as the blades and stems move transversely with said blade-stripping means.

9. In a leaf stemmer, the combination of 55 means moving with and transversely of the leaves through which the stems can be pulled but through which the blades cannot follow, and mechanism to grasp the stems and pull them from the blades including a rolling 60 member having a part cut away so that the pull on each stem is relieved during the stemming operation.

In testimony whereof, I have signed this specification.

JOSEPH GOUGH.
